UNITED STATES PATENT OFFICE

CHARLES F. ROOT, OF CLEVELAND, OHIO, ASSIGNOR TO THE CHANDLER AND PRICE COMPANY, OF CLEVELAND, OHIO, A CORPORATION OF OHIO

SHEET FEEDING MECHANISM FOR PRINTING PRESSES

Application filed March 3, 1927, Serial No. 172,346. Renewed November 13, 1930.

The present improvements, relating in general to mechanism for transferring sheets to or from printing presses, have more particular regard to mechanism of this sort intended for use with so-called Gordon or platen printing presses.

One object of the present invention is to provide such a sheet transfer mechanism that may be readily attached to existing presses with little or no alteration in their structure and that when attached or installed will not unduly encumber the press or be in the way of the operator. Another object is to provide a mechanism that will be extremely simple and compact in construction with relatively few moving parts and these so formed and disposed as not to be likely to get out of order. Still another object is to provide for necessary adjustment of parts whereby the operation of the sucker tips or equivalent sheet engaging and moving means may be adjusted so as to vary the location of the sheet on the platen of the press without requiring any change in the location of the stack of blank sheets.

To the accomplishment of the foregoing and related ends, the invention, then, consists of the means hereinafter fully described and particularly pointed out in the claims, the annexed drawings and the following description setting forth in detail certain mechanism embodying the invention, such disclosed means constituting, however, but one of various mechanical forms in which the principle of the invention may be used.

In said annexed drawings:—

Fig. 1 is a front elevation of my improved sheet transfer mechanism as attached to a press of the type in hand, the latter being shown in this as well as in the succeeding figures in dotted outline only; Fig. 2 is a side elevation of such mechanism, viewing the same as from the left in Fig. 1; Fig. 3 is a plan view thereof; Fig. 4 is a horizontal transverse section of certain parts of the mechanism with other parts in plan, the plane of the section being indicated by the line 4—4, Figs. 1 and 2; Fig. 5 is an enlarged elevational view of the head or upper portion of the support for the horizontally ex-

tending member that carries the sheet engaging and moving device; Fig. 6 is a plan view of the same; Figs. 7 and 8 are vertical sections thereof taken at approximately right angles to each other, as indicated by the section lines 7 and 8 on Figs. 5 and 6; Fig. 9 is a central section through the vertical tubular shaft that constitutes the main supporting and operating element of the mechanism, the plane of the section being indicated by line 9—9 on Figs. 2 and 4; Fig. 10 is a section at right angles to that of the preceding figure, as indicated by the line 10—10, Fig. 4; Fig. 11 is a transverse section through the guide member and adjacent parts, as indicated by the line 11—11, Fig. 2; Fig. 12 is a section through a universal joint connection between the main supporting and operating shaft and a continuation thereof that more directly supports the sheet carrying devices, the plane of the section being shown by the line 12—12, Fig. 2; Fig. 13 is a similar section showing a modification in construction; Fig. 14 is a transverse section of the latter taken on the plane indicated by line 14—14, Fig. 13; Fig. 15 is a sectional view of a valve detail; and Fig. 16 is a sectional detail of the carrier arm for the sheet engaging and moving device.

The press illustrated in the drawings, as previously indicated, is of the familiar platen or Gordon type and need not be further described than to note the oscillatorily mounted platen 1, on which the sheet requires to be placed preliminarily to being brought into contact with the form by the conjoint movement of such platen and of the opposite bed 2 which carries such form in a suitable chase (not shown). In the several general views illustrated in the drawings, the press is shown with said platen in its sheet receiving position, the registering devices as well as the grippers wherewith the platen is regularly provided for the purpose of locating the sheet and holding it in place during the printing operation being omitted.

For the purpose of illustration, I have chosen to show my improved mechanism as arranged for transferring successive sheets from a suitable table or support 3 adapted

- to hold a stack S of such sheets onto the platen 1, when in the open or sheet receiving position shown in the several figures, as just explained. It will be evident, however, that 5 the principle of operation involved may also be applied to a reversal of this operation, i. e. to the transfer of successive sheets from such platen to a stack on the table or another table similarly mounted adjacent to the press.
- 10 The detail construction of the table forms no part of the present disclosure except that, as best shown in Fig. 1, it is arranged to support the sheets on edge, i. e. in a position approximating the vertical, the lower edge of a 15 sheet, i. e. the one whereon it thus rests on the table, being designed to occupy the more advanced position after the sheet has been transferred to the platen. A vertical shaft or pillar 4, adjustable as to height, serves as 20 a support for table 3, the latter being in turn angularly adjustable about the upper end of said support. The table is also provided with an adjustable back-stop 5 and means (not shown) will desirably be provided for 25 automatically advancing such stop as the stack of sheets is depleted so that the foremost sheets s will always occupy a relatively fixed position on the table and thus with respect to the sheet transferring or feeding mechanism.
- 30 In order to transfer such sheet, it first requires to be slightly raised in the plane it normally occupies at the front of the stack S, this in order that its lower edge may clear the corresponding edge of table 3. Thereupon 35 the sheet is carried through a general arcuate path in a clockwise direction, as viewed in Fig. 3, such path at the same time curving downwardly so that the sheet when finally brought to rest will lie in contact with 40 platen 1 and be accurately positioned thereon for printing.
- The main supporting member of the sheet feeding or transferring device consists of a vertical tubular shaft 10 (see Figs. 2 and 9) 45 that is mounted so as to be capable both of oscillation about and reciprocation longitudinally of its axis. A suitable bearing 11 permitting such movement is provided for the upper end of said shaft on a bracket 12 that 50 is carried by plate 13 adapted to be attached to the one side frame of the press, e. g. the right hand side, as shown in the drawings, such plate also serving to carry various other supporting elements and operative parts, as 55 will be presently described, so that these parts may be assembled thereon wholly independently of the press. The lower end of shaft 10 is fitted around an aligned tubular shaft 14 of smaller diameter that is fixedly held in 60 another bracket 15 carried by said plate 13.
- Adjustably secured to shaft 10 is a collar 16 wherewith a roller fitted arm 18 engages. The other end of said arm is fulcrumed about a pivot 19 on plate 13 and has intermediate 65 of its ends a roller 20 that rides on a disk cam 21. The latter is adapted to be driven through suitable gears 23 from a so-called large gear 24 of the press, the ratio of the gears 23 being such that tubular shaft 10 will be raised and lowered once for every printing 70 operation of the press proper.
- There is also secured to shaft 10 directly below collar 16, by means of a clamp 17, in angularly adjustable position, an elongated segmental pinion 25 that meshes with a rack 75 26 transversely reciprocably held in suitable guides on plate 13. A compression spring 27, connected with one end of said rack through a multiplying lever 27a, tends normally to move the same to the left, as viewed 80 in Figs. 2 and 4, while the other end of the rack (see Fig. 10) is engaged by a cam 28 coaxial with cam 21 that periodically moves said rack in the opposite direction. By reason of the form of pinion 25, it will be seen 85 that oscillatory movement may be imparted to shaft 10 through the means just described, irrespective of the vertical position of said shaft due to the action of cam 21 and lever 18 which operatively connects said cam with 90 the shaft for the purpose of reciprocating the latter.
- Independently attached to the side frame 95 of the press, at a point located above plate 13, is a bracket arm 30 (see Figs. 1 and 2) that projects in an upward and outward direction so as to support substantially directly over shaft 10 a guide member 31. Such guide member in the form shown consists 100 essentially of an elongated plate with a longitudinally extending slot 32, said plate having its upper end 33 recurved and such end being oscillatorily attached to said bracket 30 about a pivot 34 lying at right angles to the plate and intersecting the slot, which, it 105 will be observed, is carried upwardly beyond such pivot. The plate is also provided with a laterally projecting portion 35 formed with an arcuate slot 36 in which is received a stud 37 mounted on bracket 30 and having a knurled nut 38 threaded on its projecting 110 end. The slot 36 is concentric with respect to pivot 34 and it will accordingly be seen that the guide member 31 may be angularly 115 adjusted about such pivot and held in predetermined fixed position within the limits of arcuate slot 36 by first loosening the nut 38 and then again tightening the same.
- Slidably held in the elongated slot 32 in 120 guide member 31 is a block 40 (see Figs. 8 and 11,) which block carries or guides a horizontally extending tubular arm 41 that constitutes the direct support for the main element of the member which in turn carries the sheet engaging and transfer devices, specifically consisting of a plurality of sucker tips 42, as will be presently described in more detail. Said tubular arm 41 is in effect a continuation of a rectangularly related tubular shaft 43 that is sealed at its upper end 125 130

as by a plug 43^a, the contiguous end 41^a of arm 41 being formed to encircle said shaft 43 and being fastened thereto as by a pin 41^b. Shaft 43 is both oscillatorily and longitudinally movably held in a head 44 from which projects laterally a stud 45, and it is this stud that is attached to the aforesaid block 40, being pivotally held in a suitable transverse bearing formed therein.

As a result of the foregoing construction, it will be seen that carrying member 41 in effect has a universal pivotal connection with said block, being free to oscillate independently about said stud 45 and about the axis 15 of tubular shaft 43. In addition, said member 41 is capable of bodily movement incidentally to reciprocation of said tubular shaft 43, of which it constitutes in effect a continuation.

Mounted on tubular shaft 43 is a surrounding tubular housing 50 that serves also to encase a compression spring 51, the lower end of which bears against a collared sleeve 52 fixed against longitudinal movement on said shaft by a clamp ring 52^a, while the upper end bears against a similar reversely disposed sleeve 53 that is integral with head 44, and forms in effect a closure for the corresponding end of the housing. It will be noted that sleeve 53 is provided with two pins 54 that slidably engage in short longitudinal slots 55 in the housing 50, whereby the housing with its appurtenant parts and the head 44 with its appurtenant parts are held against relative rotative movement, although limited reciprocatory movement is permitted between such housing and the tubular shaft 43 upon which it is mounted, on the one hand, and said head 44 on the other hand. Due to its engagement with the collars on sleeves 52 and 53, the action of spring 51 is normally to retain the shaft 43 and casing 50 (and thus head 44) against relative movement. However, it will be seen that the upward reciprocation of said shaft and housing may continue, at least until the bottoms of slots 55 contact with pins 54, even though the head be held against further movement in that direction by engagement of block 40 with the upper end of guide-slot 32.

The lower end of the tubular shaft 43 is connected with the upper end of tubular shaft 10 by means of a universal joint 60, the detail construction of which is best shown in Fig. 12. From such figure, it will be seen that not only does the joint in question permit shaft 43 to occupy any required angular relation with respect to shaft 10, but also a continuous sealed duct or passageway 60^a for air is provided through such joint between the hollow interiors of the two shafts. Figs. 13 and 14 show another similar form of universal joint 61 in which, however, the air passage is rendered continuous by interposing a short section 62 of flexible hose.

Fixedly secured to housing 50 is an angular bracket 65 to which an arm 66 is in turn pivotally attached at its lower end about an axis 66^a, the upper end of such arm carrying a roller 67 mounted on a transversely extending stud 68. The position of this roller, the axis of which it will be seen primarily lies parallel to the axis of tubular member 41, may be shifted transversely of such axis by angular adjustment of arm 66 and the latter is adapted to be held in selected position by means of a clamp screw 69 that passes through a slot 70 in bracket 65 and has threaded engagement with the upper end 75 of said arm.

Oscillatorily mounted upon tubular member 41 is a second tubular member 71 to which is attached in parallel offset relation a tubular extension 72. As best shown in Fig. 8, said member 71 is retained in place by 85 means of a washer 71^a secured to a plug 41^c that forms a closure for the corresponding end of tubular arm 41. Adjustably clamped to member 71 is a curved cam arm 73, so disposed and formed as to be adapted to engage 90 with said roller 67 as said member 71 along with member 41, upon which it is mounted, is swung in a horizontal plane incidentally to oscillation of tubular shaft 43. A tension spring 74, suitably attached at its lower end 95 to housing 50 (e. g. to the clamp 65^a whereby bracket 65 is attached to said housing), and at its upper end to a radially projecting arm 75 on tubular member 71, serves to rotate the latter in a clockwise direction, as 100 viewed in Fig. 7, so as to cause cam arm 73 at all times to bear against roller 67. The surface of the cam being shaped to form a path with a compound sweep upwardly and laterally, in riding against the roller 67 affords a control determining a rocking or oscillation of member 71; and by adjustment of the relative position of the roller along the cam, the extent of such rocking movement is 105 readily governed.

As a result of the construction just described, oscillation of shaft 43 about its axis at the same time causes member 71 to swing through a corresponding arc. The housing 50, however, being attached to the head 44, 115 does not partake of this movement nor therefore does the roller 67. Accordingly, swinging movement of member 71 at the same time automatically causes it to oscillate about its own axis.

A tubular extension 76 is telescopically adjustably held in tubular extension 72 of member 71 and such extension 76 in turn supports successive telescopic extensions 77 and 78, such extensions respectively carrying the 125 sucker tips 42, shown as three in number. The actual number, however, of such tips is a matter of choice and, if desired, they may be all carried by a single extension or for that matter could be carried directly by tu- 130

bular arm 72, except for the limitation this would impose in the matter of transverse and angular adjustment of such sucker tips.

Connected with the lower end of shaft 14 and lying at right angles thereto (see Figs. 2 and 15) is a cylindrical valve casing 80 within which reciprocably operates a hollow cylindrical valve 81. Such valve has a port 82 in its side wall that in one position is adapted to register with the opening in shaft 14 and in another position with an opening 83 to atmosphere. The valve is also provided with a laterally projecting pin 84 held in a slot 85 in the casing and projecting therebeyond so as to be engageable with the slotted lower end of a bell crank lever 86 that is pivotally attached to the plate 13 and periodically operated by means of a cam 89 coaxial with the other cams previously referred to and operating in unison therewith. The valve casing 80 is connected by means of a hose 87, or equivalent flexible duct, with a suction line 88 whereby under operating conditions a vacuum is created in the system of tubular shafts and members when the sucker tips 42 are sealed as by picking up a sheet of paper; that is, when the valve 81 is positioned with port 82 in register with the opening in shaft 14. However, with the port in register with opening 82, the vacuum is broken and the sucker tips accordingly rendered inoperative.

There is also shown in Figs. 1 and 2 an exhaust blast line 90 which is connected by means of a duct 91 with a blast device that extends along the front edge of table 3 and serves to flutter the foremost sheet *s* of the stack *S* and thus facilitate the removal of such sheet from the stack.

The detail construction of the telescopic carrier arm for the sucker tips 42 is shown in Fig. 16, which is a central longitudinal section through the outermost section 78 (see Fig. 3) and the next adjacent slightly larger section 77. Instead, however, of the smaller section directly slidably fitting within the outer end of section 77, the latter is provided with a sleeve 95 that is brazed or otherwise firmly united to the end of the tube 77. The sleeve projects slightly beyond the tube end, such projecting end being slit and being fitted with a transverse clamp screw 96, whereby it and thus the tube end may be firmly clamped around the smaller telescoping section 78. As a result of the foregoing construction, such last mentioned smaller tube, it will be seen, may project beyond the opening 97 in the larger tube leading to the corresponding sucker tip 42 without blocking off such opening as would otherwise be the case. At the same time a firm support is provided for the smaller section of the tubular arm and the latter may be secured as firmly as desired to the larger section. It will be understood that the construction as

just described is employed at each point in the tubular carrier arm where a smaller section telescopes within a larger one.

The general operation of the mechanism need only be briefly described by way of résumé, the operation of the several component parts having already been fully set forth. The stack *S* of sheets, as previously explained, is supported on table 3 so that the foremost sheet *s* will always occupy a fixed position. The position of the sheet transferring mechanism, and more particularly of the swing arm that carries the sucker tips, where the latter are disposed to engage such foremost sheet of the stack, is shown in dotted outline in each of Figs. 1, 2 and 3, the position of the parts in question as shown in full lines in said figures being the one occupied after the sheet has been moved to its proper place on the platen 1. The sheet in being thus transferred from the stack to the platen is initially raised slightly to facilitate its disengagement from the table and is then carried through an approximately 90 degree arc, at the same time being lowered, and as a result of such conjoint oscillatory and vertical movement, it is deposited on the platen substantially parallel therewith and without necessity for further shifting or other adjustment with respect to the gauges on said platen. Such adjustment of the final position of the sheet, in other words, is provided for by adjustment of guide 31 which, when angularly inclined with respect to the vertical, functions to shift the axis of oscillation of the swinging carrier arm incidentally to its vertical reciprocation. There may of course be the case where the guide is secured in vertically adjusted position, in which event such axis will not be shifted, but this would suit only one particular size of sheet at the most and a corresponding fixed location of such sheet when deposited on the platen.

However, whether thus vertically positioned or angularly inclined, the upper end of the guideway in member 31, it will be noted, at all times intersects the axis 34 about which said member is pivotally adjustable, so that when the slide 40 occupies its uppermost position, the stud support 45 of the carrier member will lie in substantial alignment with said pivotal axis when the carrier member is raised to its uppermost position. In other words, the carrier member is always returned to the same starting position so that no adjustment in location of the stack is ever necessary whether the sheets composing the stack be large or small or of different sizes at different times.

By varying the angular adjustment of guide 31, as will be best seen upon referring to Fig. 2, the forward edge of the sheet as it is deposited on the platen will be brought more or less closely adjacent the lower or

forward edge of the platen. The requisite adjustment of the guide is a very simple matter and permits of extremely accurate location of the sheet in the respect noted. The 5 transverse location of the sheet is of course determined by the transverse position initially occupied by the stack on the table.

In order to seat properly in the various positions, the sucker tips on the carrier arm obviously require to be disposed at a different angle with respect to the axis of the latter or rather of the main supporting element 41, about which the arm proper is oscillatory in the two limiting positions of the arm, and 10 such angular movement is automatically imparted during the swinging of the arm through the arcuate path just described by interengagement of cam arm 73 with roller 67. Since the adjustment of the roller carrying 15 arm 66 with relation to particular portions of the cam curve makes possible a regulation of the timing and extent of such engagement, this provides simple and convenient means for varying the amount of such angular movement 20 of the sucker tips about their axis of oscillation on supporting member 41, and adjustment for different conditions of usage is readily had. Vertical reciprocatory movement of the tubular shaft 43, which constitutes 25 the direct support for the carrier arm, is converted into movement in an angular direction whenever the guide 31 is secured in a position inclined to the vertical; that is, throughout the major portion of such vertical reciprocatory movement of the member 30 in question. However, irrespective of whether guide member 31 is inclined or not, the slide 40 is designed to reach the upper limit of its travel in the slot 32 in said guide member 35 before tubular shaft 43 is raised to its uppermost limit. The result is that said tubular shaft at this stage partakes of a slight vertical movement independently of the slide 40 and of the head 44 with housing 50 mounted 40 on said slide, in which the upper end of said tubular shaft is in turn held. This slight movement occurs just after the carrier arm has been brought into position to engage a sheet on the table 3, with the result that the 45 first movement imparted to the sheet is a slight vertical movement. Following this the sheet now disengaged from the table is lowered as tubular shaft 43 returns to its normal position with respect to head 44 and then 50 the general lowering movement of the head along with the slide, to which it is attached, follows.

Coincidentally with such vertical raising and lowering of the arm, as well as with its 55 normal lowering movement, a continuous swinging movement is of course being imparted thereto in a clock-wise direction as viewed in Fig. 3. Accordingly, the sucker tips immediately start to carry the outermost sheet, or at least the lower edge thereof, away

from the rest of the stack. The movement of such lower edge will be such as to carry it along and over the projecting front portion of inclined table 3, and, since the outer sucker tip travels on an arc of greater radius than the others, a more rapid movement will be imparted to the corresponding end of the sheet. Otherwise stated, the left hand side of the sheet as viewed in Fig. 3 will be cleared of the table in advance of the right hand side, the sheet as a whole being given a turning movement. This greatly facilitates the separation of the outermost sheet from the one next thereto, i. e. prevents the picking up of more than the one sheet.

As previously noted, all of the mechanism for operating the sheet transferring device proper is carried on a single plate 13 which is adapted to be readily attached to the side frames of existing presses. The bracket 39, 70 which carries the angularly adjustable guide member 31, is similarly capable of ready attachment to such a press, as is also the pillar 4 which supports the feed table, this being carried on a heavier bracket secured to the side frame just below plate 13. The feed table, as well as the operating mechanism for the carrier arm that constitutes the main operative element of the sheet transferring mechanism, are all located to one side of the platen 75 so as to leave the front of the latter unobstructed, an arrangement possessing obvious advantages over sheet feeding mechanisms that are located directly in front of the platen and so require to be removed whenever access 80 to the latter is necessary. The number of parts involved has been reduced to a minimum and the mechanism rendered correspondingly simple and less likely to get out of order.

Other modes of applying the principle of my invention may be employed instead of the one explained, change being made as regards the mechanism herein disclosed, provided the means stated by any of the following claims or the equivalent of such stated means be employed.

I therefore particularly point out and distinctly claim as my invention:—

1. In mechanism of the character described, the combination of a support oscillatory about and reciprocable longitudinally of an approximately vertical axis; a guide member wholly independent of and normally occupying a fixed position relatively to said support; a horizontally extending member movably attached to said guide member and carrying a sheet engaging and moving device; and connections including a universal joint between said support and said carrying member, whereby oscillatory and reciprocatory movement of the former is imparted to the latter.

2. In mechanism of the character described, the combination of a support oscillatory about and reciprocable longitudinally

of an approximately vertical axis; an adjustable guide member wholly independent of and normally occupying a fixed position relatively to said support; a horizontally extending member movably attached to said guide member and carrying a sheet engaging and moving device; and connections including a universal joint between said support and said carrying member, whereby oscillatory and reciprocatory movement of the former is imparted to the latter.

3. In mechanism of the character described, the combination of a support oscillatory about and reciprocable longitudinally of an approximately vertical axis; a guide member wholly independent of and normally occupying a fixed position relatively to said support, said guide member being adjustable in an approximately vertical plane; a horizontally extending member movably attached to said guide member and carrying a sheet engaging and moving device; and connections including a universal joint between said support and said carrying member, whereby oscillatory and reciprocatory movement of the former is imparted to the latter.

4. In mechanism of the character described, the combination of a support oscillatory about and reciprocable longitudinally of an approximately vertical axis; a guide member wholly independent of and normally occupying a fixed position relatively to said support; a horizontally extending member movably attached to said guide member and carrying a sheet engaging and moving device; and connections including a universal joint between said support and said carrying member, whereby oscillatory and reciprocatory movement of the former is imparted to the latter, the latter being also oscillatory about its own axis.

5. In mechanism of the character described, the combination of a support oscillatory about and reciprocable longitudinally of an approximately vertical axis; a guide member wholly independent of and normally occupying a fixed position relatively to said support; a horizontally extending member movably attached to said guide member and carrying a sheet engaging and moving device; connections including a universal joint between said support and said carrying member, whereby oscillatory and reciprocatory movement of the former is imparted to the latter, the latter being also oscillatory about its own axis; and means adapted thus to oscillate said carrying member incidental- ly to its reciprocatory movement.

6. In mechanism of the character described, the combination of a support oscillatory about and reciprocable longitudinally of an approximately vertical axis; a guide member wholly independent of and normally occupying a fixed position relatively to said support; a block slidably held in said guide;

a horizontally extending member pivotally attached to said block and carrying a sheet engaging and moving device; and connections including a universal joint between said support and said carrying member, whereby oscillatory and reciprocatory movement of the former is imparted to the latter.

7. In mechanism of the character described, the combination of a support oscillatory about and reciprocable longitudinally of an approximately vertical axis; a guide member wholly independent of and normally occupying a fixed position relatively to said support; a block slidably held in said guide; a horizontally extending member having a universal pivotal connection with said block and carrying a sheet engaging and moving device; and connections including a universal joint between said support and said carrying member, whereby oscillatory and reciprocatory movement of the former is imparted to the latter.

8. In mechanism of the character described, the combination of a support oscillatory about and reciprocable longitudinally of an approximately vertical axis; an adjustable guide member wholly independent of and normally occupying a fixed position relatively to said support; a block slidably held in said guide; a horizontally extending member pivotally attached to said block and carrying a sheet engaging and moving device; and connections including a universal joint between said support and said carrying member, whereby oscillatory and reciprocatory movement of the former is imparted to the latter.

9. In mechanism of the character described, the combination of a support oscillatory about and reciprocable longitudinally of an approximately vertical axis; a guide member wholly independent of and normally occupying a fixed position relatively to said support, said guide member being adjustable in an approximately vertical plane; a block slidably held in said guide; a horizontally extending member having a universal pivotal connection with said block and carrying a sheet engaging and moving device; and connections including a universal joint between said support and said carrying member, whereby oscillatory and reciprocatory movement of the former is imparted to the latter.

10. In mechanism of the character described, the combination of a horizontally extending member carrying a sheet engaging and moving device; and means supporting said member arranged and constructed to impart thereto a compound vertically reciprocatory and horizontally oscillatory movement, said means being adapted to impart an independent vertically reciprocatory movement to said member.

11. In mechanism of the character de-

scribed, the combination of a horizontally extending member carrying a sheet engaging and moving device; and means supporting said member arranged and constructed to impart thereto a compound vertically reciprocatory and horizontally oscillatory movement, said means being adapted to impart an independent vertically reciprocatory movement to said member in one angular position thereof about its axis of oscillation.

12. In mechanism of the character described, the combination of a horizontally extending member carrying a sheet engaging and moving device; means supporting said member arranged and constructed to impart thereto a compound vertically reciprocatory and horizontally oscillatory movement, said means being adapted to impart an independent vertically reciprocatory movement to said member; and means adapted to shift the axis of oscillation of said member incidentally to such reciprocation thereof.

13. In mechanism of the character described, the combination of a horizontally extending member carrying a sheet engaging and moving device; means supporting said member arranged and constructed to impart thereto a compound vertically reciprocatory and horizontally oscillatory movement, said means being adapted to impart an independent vertically reciprocatory movement to said member; and adjustable means adapted variably to shift the axis of oscillation of said member incidentally to such reciprocation thereof.

14. In mechanism of the character described, the combination of a horizontally extending member carrying a sheet engaging and moving device; means supporting said member arranged and constructed to impart thereto a compound vertically reciprocatory and horizontally oscillatory movement, said means being adapted to impart an independent vertically reciprocatory movement to said member; and a guide member for said carrying member.

15. In mechanism of the character described, the combination of a horizontally extending member carrying a sheet engaging and moving device; means supporting said member arranged and constructed to impart thereto a compound vertically reciprocatory and horizontally oscillatory movement, said means being adapted to impart an independent vertically reciprocatory movement to said member; and a guide member for said carrying member normally occupying a fixed position.

16. In mechanism of the character described, the combination of a horizontally extending member carrying a sheet engaging and moving device; means supporting said member arranged and constructed to impart thereto a compound vertically reciprocatory and horizontally oscillatory movement, said

means being adapted to impart an independent vertically reciprocatory movement to said member; and an angularly adjustable guide member for said carrying member normally occupying a fixed position.

17. In mechanism of the character described, the combination of a guide; a slide held in said guide; a head pivoted to said slide about an axis transverse of said guide; a member mounted in said head so as to be longitudinally reciprocable and oscillatory relatively thereto; and a horizontally extending member mounted on said first-named member and carrying a sheet engaging and moving device.

18. In mechanism of the character described, the combination of a guide; a slide held in said guide; a head pivoted to said slide about an axis transverse of said guide; a member mounted in said head so as to be longitudinally reciprocable and oscillatory relatively thereto; and a horizontally extending member mounted on said first-named member and carrying a sheet engaging and moving device, said carrier member being also oscillatory about its own axis.

19. In mechanism of the character described, the combination of a guide; a slide held in said guide; a head pivoted to said slide about an axis transverse of said guide; a member mounted in said head so as to be longitudinally reciprocable and oscillatory relatively thereto; and a horizontally extending member mounted on said first-named member and carrying a sheet engaging and moving device, said carrier member being also oscillatory about its own axis and including an offset extension whereto said device is attached.

20. In mechanism of the character described, the combination of a guide; a slide held in said guide; a head pivoted to said slide about an axis transverse of said guide; a member mounted in said head so as to be longitudinally reciprocable and oscillatory relatively thereto; a horizontally extending member mounted on said first-named member and carrying a sheet engaging and moving device, said carrier member being also oscillatory about its own axis; and means adapted thus to oscillate said carrier member upon oscillation of said head.

21. In mechanism of the character described, the combination of a guide; a slide held in said guide; a head pivoted to said slide about an axis transverse of said guide; a member mounted in said head so as to be longitudinally reciprocable and oscillatory relatively thereto; a horizontally extending member mounted on said first-named member and carrying a sheet engaging and moving device, said carrier member being also oscillatory about its own axis; and adjustable means adapted thus to oscillate said car-

rier member a predetermined amount upon oscillation of said head.

22. In mechanism of the character described, the combination of a guide; a slide held in said guide; a head pivoted to said slide about an axis transverse of said guide; a member mounted in said head so as to be longitudinally reciprocable and oscillatory relatively thereto; a horizontally extending member mounted on said first-named member and carrying a sheet engaging and moving device, said carrier member being also oscillatory about its own axis; and means adapted thus to oscillate said carrier member upon oscillation of said head, said means including a cam arm on said member and a fixed element on said head wherewith said arm engages.

23. In mechanism of the character described, the combination of a guide; a slide held in said guide; a head pivoted to said slide about an axis transverse of said guide; a member mounted in said head so as to be longitudinally reciprocable and oscillatory relatively thereto; a horizontally extending member mounted on said first-named member and carrying a sheet engaging and moving device, said carrier member being also oscillatory about its own axis; and means adapted thus to oscillate said carrier member upon oscillation of said head, said means including a cam arm on said member, a fixed element on said head wherewith said arm engages, and a spring adapted to retain said arm in contact with said element.

24. In mechanism of the character described, the combination of a guide; a slide held in said guide; a head pivoted to said slide about an axis transverse of said guide; a member mounted in said head so as to be longitudinally reciprocable and oscillatory relatively thereto; a horizontally extending member mounted on said first-named member and carrying a sheet engaging and moving device, said carrier member being also oscillatory about its own axis; and means adapted thus to oscillate said carrier member upon oscillation of said head, said means including a cam arm on said member, a roller secured in adjustable fixed relation to said head wherewith said arm engages, and a tension spring adapted to retain said arm in contact with said element.

25. In mechanism of the character described, the combination of a guide; a slide held in said guide; a head pivoted to said slide about an axis transverse of said guide; a member mounted in said head so as to be longitudinally reciprocable and oscillatory relatively thereto; means normally restraining such reciprocation of said member; and a horizontally extending member mounted on said first-named member and carrying a sheet engaging and moving device.

26. In mechanism of the character de-

scribed, the combination of a guide; a slide held in said guide; a head pivoted to said slide about an axis transverse of said guide; a member mounted in said head so as to be longitudinally reciprocable and oscillatory relatively thereto; a spring normally restraining such reciprocation of said member; and a horizontally extending member mounted on said first-named member and carrying a sheet engaging and moving device.

27. In mechanism of the character described, the combination of a guide; a slide held in said guide; a head pivoted to said slide about an axis transverse of said guide; a member mounted in said head so as to be longitudinally reciprocable and oscillatory relatively thereto; a compression spring surrounding said member; shoulders on the latter and said head against which said spring presses so as normally to restrain such reciprocation of said member; and a horizontally extending member mounted on said first-named member and carrying a sheet engaging and moving device.

28. In mechanism of the character described, the combination of a guide; a slide held in said guide; a head pivoted to said slide about an axis transverse of said guide; a member mounted in said head so as to be longitudinally reciprocable and oscillatory relatively thereto; a compression spring surrounding said member; shoulders on the latter and said head against which said spring presses so as normally to restrain such reciprocation of said member; a housing for said spring attached to said head; co-operative stop elements on said housing and member adapted to limit such reciprocation of the latter; and a horizontally extending member mounted on said first-named member and carrying a sheet engaging and moving device.

29. In mechanism of the character described, the combination of a guide; a slide held in said guide; a head pivoted to said slide about an axis transverse of said guide; a member mounted in said head so as to be longitudinally reciprocable and oscillatory relatively thereto; means adapted to reciprocate and oscillate said member, reciprocation of the latter carrying said head therewith; means limiting such reciprocation of said head, whereupon said member is free to reciprocate further independently thereof; and a horizontally extending member mounted on said first-named member and carrying a sheet engaging and moving device.

30. In mechanism of the character described, the combination of a guide; a slide held in said guide; a head pivoted to said slide about an axis transverse of said guide; a member mounted in said head so as to be longitudinally reciprocable and oscillatory relatively thereto; means adapted to reciprocate and oscillate said member, reciprocation

tion of the latter carrying said head therewith, said guide being formed to limit movement of said slide and thus reciprocation of said head in one direction, whereupon said member is free to reciprocate further independently thereof; and a horizontally extending member mounted on said first-named member and carrying a sheet engaging and moving device.

31. In mechanism of the character described, the combination of a guide angularly adjustable in an approximately vertical plane; a slide held in said guide; a head pivoted to said slide about an axis transverse of said guide; a member mounted in said head so as to be longitudinally reciprocable and oscillatory relatively thereto; means adapted to reciprocate and oscillate said member, reciprocation of the latter carrying said head therewith, said guide being formed to limit movement of said slide and thus reciprocation of said head in one direction, whereupon said member is free to reciprocate further independently thereof; and a horizontally extending member mounted on said first-named member and carrying a sheet engaging and moving device.

32. In mechanism of the character described, the combination of a support oscillatory about and reciprocable longitudinally of an approximately vertical axis; a guide wholly independent of and normally occupying a fixed position relatively to said support; a slide held in said guide; a head pivoted to said slide about an axis transverse of said guide; a member mounted in said head so as to be longitudinally reciprocable and also oscillatory relatively thereto; a horizontally extending member mounted on said first-named member and carrying a sheet engaging and moving device; and connections including a universal joint between said support and said first-named member whereby oscillatory and reciprocatory movement of the former is imparted to the latter.

33. In mechanism of the character described, the combination of a support oscillatory about and reciprocable longitudinally of an approximately vertical axis; a guide wholly independent of and normally occupying a fixed position relatively to said support; a slide held in said guide; a head pivoted to said slide about an axis transverse of said guide; a member mounted in said head so as to be longitudinally reciprocable and also oscillatory relatively thereto; a horizontally extending member mounted on said first-named member and carrying a sheet engaging and moving device; yielding means normally retaining said member and head against relative reciprocation; and connections including a universal joint between said support and said first-named member whereby oscillatory and reciprocatory movement of the former is imparted to the latter.

34. In mechanism of the character described, the combination of a support oscillatory about and reciprocable longitudinally of an approximately vertical axis; a guide wholly independent of and normally occupying a fixed position relatively to said support; a slide held in said guide; a head pivoted to said slide about an axis transverse of said guide; a member mounted in said head so as to be longitudinally reciprocable and also oscillatory relatively thereto; a horizontally extending member mounted on said first-named member and carrying a sheet engaging and moving device; yielding means normally retaining said member and head against relative reciprocation; means limiting reciprocation of said head; and connections including a universal joint between said support and said first-named member whereby oscillatory and reciprocatory movement of the former is imparted to the latter.

35. In mechanism of the character described, the combination of a support oscillatory about and reciprocable longitudinally of an approximately vertical axis; a guide wholly independent of and normally occupying a fixed position relatively to said support; a slide held in said guide; a head pivoted to said slide about an axis transverse of said guide; a member mounted in said head so as to be longitudinally reciprocable and also oscillatory relatively thereto; a horizontally extending member mounted on said first-named member and carrying a sheet engaging and moving device; yielding means normally retaining said member and head against relative reciprocation, said guide being formed to limit movement of said slide and thus reciprocation of said head in one direction; and connections including a universal joint between said support and said first-named member whereby oscillatory and reciprocatory movement of the former is imparted to the latter.

36. In mechanism of the character described, the combination of a support oscillatory about and reciprocable longitudinally of an approximately vertical axis; a guide wholly independent of and normally occupying a fixed position relatively to said support; a slide held in said guide; a head pivoted to said slide about an axis transverse of said guide; a member mounted in said head so as to be longitudinally reciprocable and also oscillatory relatively thereto; a horizontally extending member mounted on said first-named member and carrying a sheet engaging and moving device, said carrier member being also oscillatory about its own axis; and connections including a universal joint between said support and said first-named member whereby oscillatory and reciprocatory movement of the former is imparted to the latter.

37. In mechanism of the character de-

scribed, the combination of a support oscillatory about and reciprocable longitudinally of an approximately vertical axis; a guide wholly independent of and normally occupying a fixed position relatively to said support; a slide held in said guide; a head pivoted to said slide about an axis transverse of said guide; a member mounted in said head so as to be longitudinally reciprocable and also oscillatory relatively thereto; a horizontally extending member mounted on said first-named member and carrying a sheet engaging and moving device, said carrier member being also oscillatory about its own axis and including an offset extension whereto said device is attached; and connections including a universal joint between said support and said first-named member whereby oscillatory and reciprocatory movement of the former is imparted to the latter.

38. In mechanism of the character described, the combination of a support oscillatory about and reciprocable longitudinally of an approximately vertical axis; a guide wholly independent of and normally occupying a fixed position relatively to said support; a slide held in said guide; a head pivoted to said slide about an axis transverse of said guide; a member mounted in said head so as to be longitudinally reciprocable and also oscillatory relatively thereto; a horizontally extending member mounted on said first-named member and carrying a sheet engaging and moving device, said carrier member being also oscillatory about its own axis and including an offset extension whereto said device is attached; means adapted thus to oscillate said carrier member upon oscillation of said head; and connections including a universal joint between said support and said first-named member whereby oscillatory and reciprocatory movement of the former is imparted to the latter.

39. In mechanism of the character described, the combination of a support oscillatory about and reciprocable longitudinally of an approximately vertical axis; a guide member wholly independent of and normally occupying a fixed position relatively to said support; a horizontally extending member movably attached to said guide member and carrying a sheet engaging and moving device; connections, including a universal joint between said support and said carrying member, whereby oscillatory and reciprocatory movement of the former is imparted to the latter; means operatively connected with said support to reciprocate the same; and other means adapted simultaneously to oscillate said support.

40. In mechanism of the character described, the combination of a support oscillatory about and reciprocable longitudinally of an approximately vertical axis; a guide member wholly independent of and normally

occupying a fixed position relatively to said support; a horizontally extending member movably attached to said guide member and carrying a sheet engaging and moving device; connections, including a universal joint, 70 between said support and said carrying member, whereby oscillatory and reciprocatory movement of the former is imparted to the latter; a lever operatively connected with said support to reciprocate the same; and 75 means adapted simultaneously to oscillate said support, said means including an elongated pinion fixed on said support and a transversely reciprocable rack meshing with said pinion.

41. In mechanism of the character described, the combination of a fixed vertical tubular shaft; a tubular support sleeved at one end on said shaft so as to be oscillatory about and reciprocable longitudinally of the axis thereof; a bearing for said support above said shaft; a guide; a horizontally extending tubular member movably attached to said guide and carrying sucker tips for engaging and moving a sheet; and connections between said support and said carrier member, whereby oscillatory and reciprocatory movement of the former is imparted to the latter, an air-tight duct extending from said support to said carrier member.

42. In mechanism of the character described, the combination of a fixed vertical tubular shaft; a tubular support sleeved at one end on said shaft so as to be oscillatory about and reciprocable longitudinally of the axis thereof; a bearing for said support above said shaft; a guide wholly independent of and normally occupying a fixed position relatively to said support; a horizontally extending tubular member movably attached to said guide and carrying sucker tips for engaging and moving a sheet; and connections including a universal joint between said support and said carrier member, whereby oscillatory and reciprocatory movement of the former is imparted to the latter, an air-tight duct extending through such joint from said support to said carrier member.

43. The combination with the platen of a printing couple; of a vertical support located in a position laterally adjacent to said platen; a table located adjacent the same side of said platen so as to leave the front of the latter clear and unobstructed, said table being adapted to support a stack of sheets on edge 100 and in approximate alignment with such side; and sheet-transferring means carried by said support in approximately arcuate path between said platen and table.

44. The combination with the platen of a 115 printing couple; of a vertical support located in a position laterally adjacent to said platen; a table located adjacent the same side of said platen and adapted to support a stack of sheets on edge; and sheet-transferring means 120

carried by said support in an approximately arcuate path between said platen and table, said means also being capable of independent vertical movement.

5. 45. The combination with the platen of a printing couple; of a vertical support located in a position laterally adjacent to said platen; a table located adjacent the same side of said platen and adapted to support a stack of sheets on edge; and sheet-transferring means carried by said support in an approximately arcuate path between said platen and table, said means also being capable of independent vertical movement along two angularly related lines.

10. 46. The combination with a printing couple including a platen; of a horizontally extending member carrying a sheet engaging and moving device; means supporting said member arranged and constructed simultaneously to impart thereto a reciprocatory movement and a horizontally oscillatory movement about an approximately vertical axis located adjacent to one side of said platen; and a table located adjacent the same side of said platen and adapted to support a stack of sheets on edge.

20. 47. The combination with a printing couple including a platen; of a horizontally extending member carrying a sheet engaging and moving device; means supporting said member arranged and constructed simultaneously to impart thereto a reciprocatory movement along two angularly related lines and a horizontally oscillatory movement about an approximately vertical axis located adjacent to one side of said platen; and a table located adjacent the same side of said platen and adapted to support a stack of sheets on edge.

25. 48. The combination with a printing couple including a platen; of a horizontally extending member carrying a sheet engaging and moving device; means supporting said member arranged and constructed simultaneously to impart thereto a reciprocatory movement along two angularly related generally vertical lines and a horizontally oscillatory movement about an approximately vertical axis located adjacent to one side of said platen; and a table located adjacent the same side of said platen and adapted to support a stack of sheets on edge.

30. 49. The combination with a printing couple including a platen; of a horizontally extending member carrying a sheet engaging and moving device; means supporting said member arranged and constructed simultaneously to impart thereto a reciprocatory movement and a horizontally oscillatory movement about an approximately vertical axis located adjacent to one side of said platen; and a table located adjacent the same side of said platen and adapted to support a stack of sheets on edge, the reciprocatory

movement of said member when swung into proximity to said table being more strictly vertical than during the remainder of its oscillatory movement.

50. 50. The combination with a printing couple including a platen; of a horizontally extending member carrying a sheet engaging and moving device; means supporting said member arranged and constructed simultaneously to impart thereto a reciprocatory movement and a horizontally oscillatory movement about an approximately vertical axis located adjacent to one side of said platen; and a table located adjacent the same side of said platen and adapted to support a stack of sheets on edge, the reciprocatory movement of said member when swung into proximity to said table being along a strictly vertical line and being along an angularly related line during the remainder of its oscillatory movement.

55. 51. The combination with a printing couple including a platen; of a horizontally extending member carrying a sheet engaging and moving device; means supporting said member arranged and constructed simultaneously to impart thereto a reciprocatory movement and a horizontally oscillatory movement about an approximately vertical axis located adjacent to one side of said platen; and a table located adjacent the same side of said platen and adapted to support a stack of sheets on edge, the reciprocatory movement of said member when swung into proximity to said table being along a strictly vertical line and being along a line of adjustable angularity to the vertical during the remainder of its oscillatory movement.

60. 52. In a method of transferring a sheet from a stack supported on edge to an approximately horizontal platen, the step which consists in imparting to the lower edge of such sheet a compound vertically reciprocatory movement and a horizontally oscillatory movement about an approximately vertical axis.

65. 53. In a method of transferring a sheet from a stack supported on edge to an approximately horizontal platen, the step which consists in imparting to the lower edge of such sheet a compound vertically reciprocatory movement along two angularly related lines and a horizontally oscillatory movement about an approximately vertical axis.

70. 54. In a method of transferring a sheet from a stack supported on edge to an approximately horizontal platen, the step which consists in imparting to the lower edge of such sheet a compound vertically reciprocatory movement along two angularly related generally vertical lines and a horizontally oscillatory movement about an approximately vertical axis.

75. 55. In a method of transferring a sheet from a stack supported on edge to an ap-

- proximately horizontal platen, the step which consists in imparting to the lower edge of such sheet a compound vertically reciprocatory movement and a horizontally oscillatory movement about an approximately vertical axis, such reciprocatory movement being more strictly vertical at the beginning than during the remainder of the oscillatory movement of the sheet.
56. In a method of transferring a sheet from a stack supported on edge to an approximately horizontal platen, the step which consists in imparting to the lower edge of such sheet a compound vertically reciprocatory movement and a horizontally oscillatory movement about an approximately vertical axis, such reciprocatory movement being along a strictly vertical line at the beginning of the oscillatory movement, and being along an angularly related line during the remainder of the oscillatory movement of the sheet.
57. In mechanism of the character described, the combination of a tubular carrier arm section having a lateral opening, a section telescopic within said first-named section, and a spacer between said sections whereby such lateral opening remains unobstructed in all positions of the telescopic section.
58. In mechanism of the character described, the combination of a tubular carrier arm section, a section telescopic within said first-named section, a sheet-engaging tip on said telescopic section, and a sleeve interposed between said sections.
59. In mechanism of the character described, the combination of a tubular carrier arm section, a section telescopic within said first-named section, a sheet-engaging tip on said telescopic section, and an interposed sleeve projecting from the end of said first-named section, said sleeve being slit at its exposed end and having a tightening screw.
45. Signed by me, this 26th day of February, 1927.

CHARLES F. ROOT.
